W. JONES

SHEARS SHARPENER

Filed Sept. 9, 1921

Inventor

Walter Jones

Louis G. Griswold,

Attorney

UNITED STATES PATENT OFFICE.

WALTER JONES, OF CLEVELAND, OHIO.

SHEARS SHARPENER.

Application filed September 9, 1921. Serial No. 499,461.

To all whom it may concern:

Be it known that I, WALTER JONES, a citizen of the United States, residing at Cleveland, in the county of Cuyahoga and 5 State of Ohio, have invented certain new and useful Improvements in Shears Sharpeners, of which the following is a specification.

This invention relates to an improved device for sharpening shears, scissors and the 10 like, and it has for its primary object the provision of a simple, durable, economical, and efficient device of the character set forth.

Another object of the invention is to provide means for adjusting the device so that 15 the shears may be sharpened at any desired angle, and for otherwise changing the relation of the elements thereof for utilizing the entire area of the grinding member so that when one portion of said grinding element 20 becomes worn an unworn portion may be readily brought into action.

A further object of the invention is to provide a device of this class that is light and 25 non-cumbersome, adapting it to be carried in a pocket of one's wearing apparel.

With these and other apparent objects in view, the invention consists in the construction, combination and arrangement of elements as hereinafter described and pointed 30 out definitely in the claims, reference being had to the accompanying drawings which are made part of the specification, similar characters of reference being employed to designate corresponding parts.

35 In the said drawings Fig. 1 is a side elevation of the improved device.

Fig. 2 is a top view.

Figs. 3 and 4 are back and front elevations, respectively.

40 Fig. 5 is a back elevation of the supporting bracket detached, and Fig. 6 is a side view of same.

Fig. 7 is a top view of the oscillatable leaf member.

45 Fig. 8 is a side elevation illustrating a modified form of adjustment.

The embodiment of the invention as shown in Figs. 1 to 7, inclusive, includes a supporting bracket 1 having an upright plain wing 1^a and an integral base plain wing 1^b, a 50 medial loop 1^c connecting said wings, with the angle portion broken out on both sides of said loop forming recesses as shown at 1^d. A movable plate, or leaf element 2 is provided with loops 2^a which are adapted to fit the 55 recesses 1^d, and co-acting with a pintle 3

which passes through said loops 2^a and loop 1^c, forms a hinge connection between the elements 1 and 2. A screw 3^a anchors the pintle 3 in the loop 1^c. An arcuate screw 4 having the pintle 3 as its radius center, is attached to the base element 1^b. This screw passes through an aperture 2^b, Fig. 7, and has a knurled adjustment member 5 threaded thereon below the member 2, said member 5 bearing on the underside of the member 2 and operative between said member 2 and the wing 1^b.

The movable member 2 carries an abrasive element 6, preferably a flat file, said abrasive element being removably fixed on the upper face of the member 2. In the present embodiment the file 6 abuts the loop terminals 2^c and is held in fixed condition by the pivoted finger 7 being operated on by a cam element 8. It will be understood, however, that the abrasive element 6 may be anchored to the member 2 by other adjustable means without departure from the broad principles of the invention.

A guide member 9 is attached to the upright bracket element 1^a, said guide being vertically adjustable through the medium of set screws 10 operating in slots 1^e, and having a forward, and back adjustment by means of shims 11 which are adapted to be inserted between the member 9 and element 1^a, the screws 10 passing through apertures provided in said shims.

In service the shear blade, which is indicated by broken lines in Fig. 1, is given a reciprocating movement with the cutting edge bearing on the abrasive element 6 and guided by the element 9 thereby grinding the edge of the blade on an angle corresponding to the angular adjustment of the member 2. The fore and aft adjustment of the guide element 9 shifts the shear blade relatively to the grinding element, and this together with the possibility of removing and replacing the member 6 in a reverse position, either end for end, or laterally, provides economy, by the utilization of the entire abrasive area of said member 6.

In the modification illustrated in Fig. 8, 105 the angular adjustment is brought about through the medium of a conical wedge 12 being operated by a screw 13 threaded in a lug 14 which is fixed on the base element 1^b.

It will be understood that I am not confined to the specific embodiment as shown, minor changes in details of construction, de-

2
sign, and arrangement of parts being within the scope of the invention as set forth in the appended claims.

What I claim and desire to secure by Letters Patent is:

1. In a shear sharpening device, the combination of a fixed angle bracket; an adjustable leaf hinged in the angle of said bracket; an abrasive element removably mounted on said leaf; means for arcuately adjusting the angular relation of said abrasive element to the bracket; and an adjustable guide attached to the bracket.
2. In a shear sharpener, the combination of a supporting bracket having an upright

flat plate element and a flat base element, said elements being disposed in angular relation; an oscillatable leaf element hinged in the angle of said bracket; an abrasive element mounted on said leaf; means for adjustably anchoring said abrasive element; a guide element attached to the upright bracket element; means for vertically adjusting said guide; means for lateral adjustment of said guide; and adjustment means for changing the angular relation of the abrasive element and the guide.

In testimony whereof I affix my signature.

WALTER JONES.
